MAGNETIC TAPE TRANSPORT

Walter J. Cheney, San Mateo, and Charles F. Grossman,
Sunnyvale, Calif., and Marvin A. Southcott, Baltimore,
Md., assignors to Ampex Corporation, Redwood City,
Calif., a corporation of California

Filed May 13, 1965, Ser. No. 85,266

Term of patent 14 years

(Cl. D26—5)

FIG. 1

FIG. 2

FIG. 2

FIGURE 4

FIGURE 1 is a front and right side perspective view of a magnetic tape transport, showing our new design;

FIGURE 2 is a front elevational view, with the cover door open;

FIGURE 3 is a rear and left side perspective view thereof; and

FIGURE 4 is a front, top and right side fragmentary perspective view, to an enlarged scale, showing the tape handling portions of the apparatus shown in FIGURE 2.

We claim:

The ornamental design for a magnetic tape transport, substantially as shown and described.
